US00D832222S

(12) **United States Design Patent** (10) **Patent No.:** **US D832,222 S**
(45) **Date of Patent:** **** Oct. 30, 2018**

(54) **INSULATOR**

(71) Applicants: **Bethel Idiculla Johnson**, Attleboro, MA (US); **Brad Bell**, New Buffalo, MI (US)

(72) Inventors: **Bethel Idiculla Johnson**, Attleboro, MA (US); **Brad Bell**, New Buffalo, MI (US)

(73) Assignee: **SWITCHBOARD APPARATUS, INC.**, Elmhurst, IL (US)

(**) Term: **15 Years**

(21) Appl. No.: **29/578,879**

(22) Filed: **Sep. 26, 2016**

(51) LOC (11) Cl. **13-03**

(52) U.S. Cl.

USPC **D13/155**

(58) **Field of Classification Search**

(57) **CLAIM**

The ornamental design for an insulator, as shown and described.

DESCRIPTION

FIG. 1 is a rear perspective view of an insulator showing our design;

FIG. 2 is a front perspective thereof;

FIG. 3 is a top view thereof;

FIG. 4 is a bottom view thereof;

FIG. 5 is a first side view thereof;

FIG. 6 is a second side view thereof;

FIG. 7 is a front view thereof; and,

FIG. 8 is a rear view thereof.

The broken lines represent portions of the insulator that form no part of the claimed design.

1 Claim, 8 Drawing Sheets
